DESIGN FOR A SERVICE STAND FOR THE DISPLAY OF HORS D'OEUVRES

Alexander Karsh, New York, N. Y.

Application November 22, 1935, Serial No. 59,698

Term of patent 3½ years

To all whom it may concern:

Be it known that I, Alexander Karsh, a citizen of the United States of America and resident of the city, county, and State of New York, have invented a new, original, and ornamental Design for a Service Stand for the Display of Hors d'œuvres, of which the following is a specification, reference being had to the accompanying drawing, forming a part thereof.

In the drawing:—

for the display of hors d'œuvres showing my new design.

I claim:—

The ornamental design for a service stand for the display of hors d'œuvres substantially as shown.

ALEXANDER KARSH.
